UNITED STATES PATENT OFFICE.

CHARLES H. SAUVAN, OF NEWARK, NEW JERSEY.

GAS-ENGINE.

1,013,619.

Specification of Letters Patent.

Patented Jan. 2, 1912.

Application filed January 26, 1909. Serial No. 474,207.

To all whom it may concern:

Be it known that I, CHARLES H. SAUVAN, a citizen of the United States, residing at Newark, in the county of Essex and State of New Jersey, have invented certain Improvements in Gas-Engines, of which the following is a specification.

This invention relates more particularly to the construction of the piston of a gas engine, and the objects of the invention are to secure a complete exhaust of the cylinder after an explosion and thus wholly clean out of said cylinder the gases resulting from such explosion, so that when the new charge enters it will not become mixed with a remainder of such gases; to enable the cylinder to be charged without any possibility of drawing from the exhaust; to reduce the strain and shock upon the parts of the engine; to save and conserve the energy of the engine, and thus secure more effective power, to provide a simple, durable construction, and to obtain other advantages and results as may be brought out in the following description.

Referring to the accompanying drawings, in which like numerals of reference indicate corresponding parts in each of the several figures, Figure 1 is a longitudinal sectional view of the piston and cylinder of an engine of my improved construction, and Fig. 2 is a similar view showing the parts in different position.

The engine shown is of the four cycle type, and Fig. 1 shows the position of parts at the end of the fourth cycle or beginning of the first, and Fig. 2 shows the position of the parts at the end of the second cycle or beginning of the third. In said drawings, 25 10 indicates a cylinder for the piston 11, said piston being connected by a rod 12 to the crank 13 of the shaft 14. Said cylinder is at its sides jacketed or provided with chambers 15 in any suitable and ordinary manner, and at its end or head are fuel and exhaust chambers 16 and 17, respectively, which are wholly separate from each other. The fuel chamber 16 has a port 18 to which fuel gas may be supplied in any manner 40 common to gas engines, and the chamber 17 has an outlet port 19 which may open into the atmosphere, or otherwise as desired. The main exhaust of the engine is at its side, as shown at 20.

From each of the chambers 16 and 17 ports lead to the cylinder and are controlled

by puppet valves 161, 171, respectively, shown as adapted to open inwardly to the cylinder, and having springs 162, 172 on their stems outside the cylinder head to normally hold said valves closed.

The piston 11 comprises an outer cylindrical section 21 closed at its inner end and provided adjacent thereto with the usual packing rings 22, and an inner section 23 adapted to slide in said outer section and being connected to the rod 12 by a wrist-pin 24 in any suitable and ordinary manner. Said inner section has packing 25 to make it fit tight in the outer section, so that there is an inclosed air space 29 between the two sections. The size of this air space is shown as reduced by a filler 26 inserted therein and fastened to the section 23 by a bolt 27; obviously by different sizes of fillers the capacity of the chamber between the two piston sections can be made whatever desired. A helical spring 28 is arranged between the two piston sections in the chamber 29, preferably surrounding the filler 26, as shown, and exerts its tension to hold said piston sections apart. The outside diameter of this spring 28 is substantially that of the air chamber and thus the spring is held substantially in axial coincidence with the piston sections. Furthermore, the filler 26 fits into said spiral spring 28 for a considerable portion of its length, and thus the said spring is additionally held against lateral displacement. An inwardly opening puppet valve 30 in the piston section 23 permits intake of air to the chamber 29 to replace any that may have escaped by leakage or the like and thus prevent a partial vacuum.

At the outer end of the piston 11 a ring 31 is screwed into the outer section 21, which ring provides a cylindrical flange 32 concentric with the outer section and forming therewith a chamber to receive an annular plunger 33 on the inner piston section 23. 95 Cushioning means are thus provided, whereby when the inner section slides outward of the cylinder with respect to the outer section air is compressed in the annular chamber of the said ring 31. Obviously a cushioning spring could be employed for the same purpose. Preferably the inner edges of the flange 32 of the ring 31 have tapering slits 34 which allow a limited leakage and thus more gradual cushioning.

Upon the cylinder head is a bracket 35 in which is fulcrumed a lever 36 adapted at

one end as 37 to push the valve 171, and at its other end or arm being pivoted to a connecting rod 38 adapted to slide longitudinally in suitable bearings 39 at the side of the cylinder. The end of this rod 38 is engaged by a cam 40 which is rotated by the shaft 14 through gears 41, 42 which reduce the motion to cause said cam to rotate once for every two rotations of the crank shaft.

10 In operation, the parts being as shown in Fig. 1, the first cycle simply withdraws the entire piston 11 from the cylinder without materially changing the relation of its outer and inner sections. This movement of the piston of course does not uncover the exhaust 20, but the suction of it draws in a charge of fuel through the valve 16. During the second cycle, the inner section of the piston of course returns to the position shown in Fig. 1, but the outer section of the piston is compressing the charge of fuel, and compresses the spring 28 and air in the chamber 29 so that the relation of the two piston sections is as shown in Fig. 2. At 15 this point the explosion occurs and the first momentary effect of it is to compress the spring 28 and air in the chamber 29 still further and force the outer section of the piston closer to the inner section. This 20 cushions the sudden and violent impact against the crank 13 and connecting parts of the engine, and at the same time stores up energy which is later exerted to accelerate the outward movement of the piston. 25 The piston moves outward until it uncovers the exhaust port 20 when the cylinder chamber is vented, and the third cycle is completed. On the fourth cycle the piston is returned to the position shown in Fig. 1 by 30 the combined movement of the inner section and the expansion of the spring 28, and air between the piston sections, and this enables the gases left from the explosion to be entirely cleaned out of the cylinder. To 35 provide escape for such gases, the valve 171 is opened at this time by the cam 40 sliding the rod 38 and swinging the lever 36. When a new charge is afterward admitted, it thus enters a perfectly clean chamber.

40 The spring 28 between the two piston sections is preferably a light spring, and may

even, under some circumstances, be dispensed with entirely.

Having thus described the invention, what I claim is:

55 1. In a gas engine, the combination of a cylinder, a hollow piston section in said cylinder, a second piston section in said hollow section having a transverse partition forming with the closed end of the hollow section a closed air chamber, said partition providing at its side next said chamber a filling-piece seat, a separable filling piece mounted on said seat and adapted to reduce the capacity of the cylinder, means detachably connecting said filling piece to its said seat, a single helical spring inclosing and fitting around said filler and supported thereby with its convolutions lying loosely between the filling piece and piston sections, 60 whereby a single pressure distributed over the area of each piston end is secured and the spring held against lateral displacement with economy of space, and inlet and exhaust ports for said cylinder.

75 2. In a gas engine, the combination of a cylinder, an outer cylindrical piston section, an inner piston section in said outer section, means tending to hold said piston sections resiliently apart, a ring at the outer end of 80 the outer piston section projecting thereinto and forming therewith an inwardly-facing annular recess or chamber, said ring having slits in its inner edge, an annular plunger on the inner piston section adapted to enter 85 said recess or chamber and fit the same, and inlet and exhaust means for said cylinder.

90 3. In a gas engine, the combination of a cylinder, an outer cylindrical piston section, an inner piston section in said outer section, 95 a ring in the projecting end of the outer piston section forming therewith an annular recess or chamber and having tapering longitudinal slits in its edge, an annular plunger on the inner piston section adapted to enter said recess or chamber, and inlet and exhaust means for said cylinder.

CHARLES H. SAUVAN.
